Specification of Letters Patent.

Patented Mar. 7, 1916.

Application filed April 30, 1915. Serial No. 24,929.

To all whom it may concern:

Be it known that I, MAY H. STOHR, a citizen of the United States, residing at Paterson, in the county of Passaic and State 5 of New Jersey, have invented certain new and useful Improvements in Suspenders, of which the following is a specification.

This invention relates to that class of apparel suspenders in which the main straps 10 of the suspenders cross each other at the back and are there secured together. The means for securing the members together constituting these straps has heretofore allowed them to have no free pivotal move- 15 ment on each other, so that the members frequently buckle adjoining their intersection and, where the securing means consists of stitching, in consequence soon or late disrupt the latter, leaving the two members 20 unconnected with each other.

My object is to provide a pair of suspenders of the kind indicated above with a means to secure the main straps thereof together where they cross each other in a substantial and durable manner and allow them 25 perfect freedom of pivotal movement upon each other, without ability to separate.

In the accompanying drawing, Figure 1 is a front elevation of a pair of suspenders 30 constructed in accordance with this invention; Fig. 2 is a rear elevation of the back part of the suspenders; Fig. 3 is a sectional view taken through the intersecting portions of the main suspender straps, the pivoting 35 means appearing in elevation; and, Fig. 4 is a similar view, said means appearing in section.

a a' in the drawings indicate the main straps of the suspenders, crossed in the usual 40 manner at the back and at their rear ends provided with tabs or extensions *b* having the usual button-holes.

c designates the minor or front straps 45 suitably connected with the front ends of the main straps *a a'* and provided with the usual button-holes.

Copies of this patent may be obtained for five cents each, by addressing the "Commissioner of Patents, Washington, D. C."

The straps or members *a a'* where they cross each other are secured together so as to have free pivotal movement relatively to each other as follows: *d* and *e* denote the 50 two parts of a gromet which are made to clamp between them the strap *a*, the part *d* having its upstanding stud *d'* passed through a hole in the corresponding strap and expanded to grip the inside of the up- 55 standing stud *e'* of the part *e*. *f* and *g* denote the two parts of a gromet which are made to clamp between them the other strap *a'*, the part *f* having its upstanding stud *f'* passed through a hole in the corresponding 60 strap and expanded to grip the hole *g'* in the part *g*. The construction is such that the gripping action of the parts of each gromet on the corresponding strap holds them immovably thereto. The stud *e'* of the 65 part *e* of the one gromet is introduced into the hollow stud *f'* of the part *f* of the other gromet and has its free end upset, as at *h*, to form a shoulder which retains the two 70 gromets inseparably coupled together. Thus the two straps *a a'* of the suspenders are 75 coupled so as to pivot or swivel one on the other only. It will be noted that since each gromet includes two parts clamped together against the corresponding strap, each part moreover offering a broad flat surface to the strap, there is a secure holding of the fabric or other material of the strap by the gromet.

Having thus fully described my invention, 80 what I claim as new and desire to secure by Letters Patent is:—

A connecting device of the class described including a pair of two-part gromets, the parts of each gromet being adapted to clamp 85 between them one of the members to be connected and each gromet having a pivotal bearing on the other gromet and inseparably connected therewith.

In testimony whereof I affix my signature. 90

MAY H. STOHR.
